UNITED STATES PATENT OFFICE.

ALFRED A. SPADONE, OF NEW YORK, N. Y., ASSIGNOR TO THE GUTTA PERCHA & RUBBER MANUFACTURING COMPANY, OF NEW YORK, N. Y., A CORPORATION OF NEW YORK.

DESIGN FOR TILING.

No. 39,019.

Specification for Design.

Patented Jan. 14, 1908.

Application filed October 28, 1907. Serial No. 399,618. Term of patent 14 years.

To all whom it may concern:

Be it known that I, ALFRED A. SPADONE, a citizen of the United States, and a resident of the borough of Manhattan, city, county, and State of New York, have invented a new, original, and ornamental Design for Tiling, of which the following is a specification.

Reference is to be had to the accompany-

ing drawing, illustrating a face view of tiling showing my new design.

I claim:

The ornamental design for tiling as shown.
ALFRED A. SPADONE.
